UNITED STATES PATENT OFFICE.

ALBERT B. HANEL, OF MILWAUKEE, WISCONSIN.

DIP-NET.

1,387,393.

Specification of Letters Patent.

Patented Aug. 9, 1921.

Application filed April 14, 1919. Serial No. 289,946.

To all whom it may concern:

Be it known that I, ALBERT B. HANEL, a citizen of the United States, residing at Milwaukee, county of Milwaukee, and State 5 of Wisconsin, have invented new and useful Improvements in Dip-Nets, of which the following is a specification.

My invention relates to new and useful improvements in folding dip nets, and has 10 for its object, the provision of improved means for securing the hoop bows or rim sections in position for use, the securing means being of such character as to facilitate adjusting the bows to either an extended 15 or a folded position, and to also facilitate the removal and replacement of nets.

In the drawings,—

Figure 1 is a plan view of my improved net, with its parts set up in extended position, and with the connecting portions of 20 the rim sections broken away.

Fig. 2 is a view showing the rim sections detached from the handle and folded.

Fig. 3 is a view of the connecting means 25 for the outer ends of the rim sections, showing the sections held in distended position.

Fig. 4 is a view similar to Fig. 3, but showing the connecting plate for the rim section rotated to permit folding of the 30 sections.

Referring now more particularly to the accompanying drawing, the rim or hoop of my improved dip net is formed of a pair of semi-circular flat metal sections or bows 35 1 and 2, respectively, to which is secured the net fabric 3, as hereinafter explained, the bows being slipped through the meshes of the fabric.

For detachably securing the bows to a 40 handle 4, each bow is provided at one end with a shank 5 which preferably comprises an integral extension of the section. The end portion of the shank is provided with a thickened head having a shoulder 6. The 45 head and also the shoulder may be conveniently formed by folding the extremity of the shank backwardly as shown. These shanks 5 are adapted to fit diametrically opposed longitudinal channels 7 in the handle 50 4. A ferrule 8 is fitted over the end of the handle and covers the channels therein except at the inner ends of the channels where a portion is exposed substantially equal in length to the folded portions of the shanks

55. The bows are resilient, and when the ends opposite the shanks are connected in position for use as hereinafter described, the resiliency of the metal will tend to cause a separation of the shanks, whereby said shanks are pressed outwardly in the channels 60 7 against the inner surfaces of the ferrule 8. When in position for use the shoulder at 6 will abut the inner margin of the ferrule, whereby the shanks are prevented from withdrawing from the handle 65 unless they are first pressed inwardly to the bases of the channels 7. The handle 4 is reduced to receive the ferrule and the inner ends of the channels 7 extend into the larger or thicker portion of the handle, whereby 70 the shoulders 6, and in fact, the entire folded portions of the arms 5, are protected by the walls of the channel against accidental pressures which might otherwise permit a release of the shanks by pushing the 75 shoulders inwardly from their engagement with the inner ends of the ferrule.

In order to increase the resilient pressure upon the shouldered portions of the shanks 5 and to cause them to firmly seat in the 80 channels, the intermediate portions of said shanks 5 are preferably transversely beaded as shown at 9 and bowed as shown at 9'.

At the outer side of the net, the rim sections 1 and 2 are foldably connected by a 85 coupling disk 10 having a centrally disposed post 11, and forming a seating for the notched ends of the bows, the coupling disk 10 being provided with eccentric slots 12 in which pins or rivets 13 are loosely engaged, 90 these pins being rigidly connected with their respective bows near said notched extremities, and constituting stud projections on the bows, having their outer ends headed to prevent them from withdrawing through the 95 slots. The post 11 may be fastened to the disk 10 in any suitable manner, as by soldering, threading, riveting, welding, brazing, etc. The slots 12 are diametrically opposed, each slot curving from the end nearest to 100 the post 11 to a point about 90° distant from such end, and at a progressively increasing radius. The more distant ends of the slots are provided with radial extensions 14.

The stud projections or headed pins 13 105 are in such relation to the coupling disk, that when the bows are swung to position for use in the form of a complete ring, their

notched ends will be drawn by the eccentric margins of the disk slots substantially into abutting contact with the central post 11, embraced by the notched ends, as shown in Fig. 3.

When the bows are connected with the handle, the resilience of the material will tend to cause the bows to assume a true circular form in which they will diverge from the central portion of the disk 12, which disk is of course in a plane tangential to such a circle, but the heads of the stud 13, being of greater diameter than the slots 12, prevent the studs from being withdrawn from these slots, and develop a binding frictional pressure upon the coupling disk. This fact, and the fact that the notched ends of the bows are substantially in abutting contact along a line transverse to the bows, makes it virtually impossible for the bows to accidentally fold under ordinary conditions.

But when it is desired to fold the bows, there are two methods by which this may be easily accomplished. One method is to first push the shank heads inwardly in the handle slots or channels until the shoulders 6 and the heads may pass within the ferrule, and allow the shanks to be withdrawn. This will partially relieve the resilient tension upon the bows. The ends of the bows which are connected by the coupling disk 10 may then be flattened by downward pressure upon their outer faces until the coupled end portions conform approximately to a straight line, whereupon the bows may be easily swung and folded upon each other.

The other method of folding the bows is to first apply pressure to the ends which are coupled by the disk 10, and then rotate the disk to a position where the headed studs 13 may pass into radial extensions 14 of the slots 12, thereby relieving the tension on the bows. This method facilitates the release of the shanks, since the heads of the shanks may be more easily pushed inwardly and withdrawn through the ferrule.

When the bows are detached from the handle, the shanks may easily be passed through the meshes of the net 20 at the mouth or open end of the net, and the net may be thus slipped into position upon the bows as plainly illustrated in Fig. 5. The net will preferably be thus adjusted to the bows while the latter are in a folded, or partially folded, position, after which the bows will be swung to position for use to distend the mouth of the net preferably under tension.

I claim:—

1. A foldable net, comprising a rim formed of a pair of bows, an oscillatory coupling member having eccentrically curved slots in which the bows are slidably engaged at one side of the rim, and a handle adapted to removably connect the ends of the bows at the other side of the rim, said coupling member being adapted, in one position of adjustment, to hold the bows in a common plane with their ends substantially in abutting contact. 60 65 70

2. A foldable net, comprising a net supporting rim formed of a set of resilient bows, a net thereon, a coupling for the outer ends of the bows, a pair of radially projecting shanks integral with their inner ends, a handle having longitudinal channels adapted to removably receive the shanks, and a ferrule for a portion of said channels, the ends of said shanks having shouldered heads to engage the inner margin of the ferrule, and said bows being adapted, when unfolded, to exert a resilient spreading pressure on the shanks. 75 80

3. A foldable net, comprising a net supporting rim formed of a set of resilient bows, a net thereon, a coupling for the outer ends of the bows, a pair of radially projecting shanks integral with their inner ends, a handle having longitudinal channels adapted to removably receive the shanks, and a ferrule for a portion of said channels, the ends of said shanks having shouldered heads to engage the inner margin of the ferrule, and said bows being adapted, when unfolded, to exert a resilient spreading pressure on the shanks, said shanks being adapted, when released from the handle, to pass through the meshes of a net, and to direct the bows therethrough to release or replace the net. 85 90 95 100

4. A foldable net, comprising a rim formed of a pair of bows, an oscillatory coupling member having eccentrically curved slots in which the bows are slidably engaged at one end of the rim, and a handle to removably connect the ends of the bows at the other side of the rim, said coupling member being adapted in one position of adjustment to hold the bows against rotation and in a common plane with their ends substantially in abutting contact. 105 110

In testimony whereof I affix my signature in the presence of two witnesses.

ALBERT B. HANEL.
